J. C. SHEPHERD

MEANS FOR UNITING CONCRETE REINFORCEMENTS

Filed Aug. 12, 1921

Inventor:
James C. Shepherd
By Cash, McCaulley 911

UNITED STATES PATENT OFFICE.

JAMES C. SHEPHERD, OF ST. LOUIS, MISSOURI, ASSIGNOR TO LACLEDE STEEL COMPANY, OF ST. LOUIS, MISSOURI, A CORPORATION OF MISSOURI.

MEANS FOR UNITING CONCRETE REINFORCEMENTS.

Application filed August 12, 1921. Serial No. 491,724.

To all whom it may concern:

Be it known that I, JAMES C. SHEPHERD, a citizen of the United States of America, and a resident of the city of St. Louis and State of Missouri, have invented certain new and useful Improvements in Means for Unitting Concrete Reenforcements, of which the following is a full, clear, and exact description, reference being had to the accompanying drawings, forming a part of this specification.

This invention relates to improvements in means for uniting concrete reenforcements, one of the objects being to provide a simple means whereby reinforcing elements can be easily and quickly assembled to produce a strong reenforcement having its several elements accurately located in predetermined positions. The invention is especially adapted for use in a reinforcing structure having a series of reinforcing elements and a bar, or rod, crossing the several reinforcing elements. For example, a well known type of reenforcement comprises a number of bars located within a long spiral and engaging the inner faces of the coils of the spiral. These coils should be accurately spaced and securely held to prevent accidental displacement of the coils relative to the long bars.

Prior to this invention, the long bars have been placed within the long spiral, and then secured to the coils of the spiral, usually by means of numerous individual attaching devices. These devices are intended to uniformly space the coils and at the same time secure them to the long bars. Obviously, considerable time is required to properly assemble a very large number of individual attaching devices, and this is especially true of the old methods which involve the operations of arranging the long bars within the spiral before the attaching devices are applied to the reenforcement.

According to the preferred form of the present invention, the long bars are merely inserted through eyes in a spacing device on the spiral and then turned to securely unite the several elements of the reenforcement.

The new spacing device is preferably provided with a row of open loops adapted to receive the coils of a spiral, and a row of

aligned eyes through which the long bar is inserted. After the bar has been applied to the spacer, it closes the open loops to confine the coils in said loops. The bar is then turned to a position wherein it interlocks with the eyes, and this prevents accidental displacement of the several elements. To accomplish this result, the bar is preferably non-circular in cross-section and the eyes are non-circular, these parts being so formed that the eyes serve as yielding detents adapted to secure the longitudinal bar to the spacer.

With the foregoing and other objects in view, the invention comprises the novel construction, combination and arrangement of parts hereinafter more specifically described and illustrated in the accompanying drawings wherein is shown the preferred embodiment of the invention. However, it is to be understood that the invention comprehends changes, variations and modifications which come within the scope of the claims hereunto appended.

Fig. I is a horizontal section through a metal reenforcement equipped with a spacing device embodying the features of this invention.

Fig. II is a fragmentary side elevation of the reenforcement.

Fig. III is a fragmentary view showing one of the reinforcing bars with a portion of a spacer mounted thereon, and portions of the coils secured by the spacer.

Fig. IV is an enlarged transverse section showing one of the reinforcing bars and one of the eyes surrounding the bar.

Fig. V is a view similar to Fig. IV showing the bar as it appears when it is turned to interlock with the gripping eye.

Fig. VI is a view similar to Fig. V showing another form of the invention.

To illustrate the invention I have shown spacing devices applied to a metal reenforcement for a concrete column, and this reenforcement includes a reinforcing member A in the form of a long spiral, and bars B arranged longitudinally of the spiral and engaged with the inner faces of the coils of the spiral. These coils are accurately spaced apart and secured to the longitudinal bars through the medium of the spacing device.

To illustrate this feature of the invention, I have shown a long spacer associated with each bar B. Each spacer may be made of a single piece of wire provided with a 5 row of gripping eyes 1 surrounding one of the bars B, and a row of spacing elements 2 uniting said gripping eyes, said row of spacing elements being arranged longitudinally of the bar. Each spacing element 2 10 may be provided at one of its ends with a U-shaped loop 4 merging into and extending from one of the gripping eyes 1. The coils of the spiral A are located in the U-shaped loops 4, and the open sides of 15 loops 4 are closed by the longitudinal bars B, as shown most clearly in Fig. III.

In each spacing device, the eyes 1 are in alinement with each other, and the loops 4 are also in alinement with each other. 20 The loops 4 extend from one side of the spacing device and the eyes 1 extend from the other side. The loops 4 are open at the side from which the eyes 1 extend (Fig. III) and each eye 1 is arranged at approximately 25 a right angle to the loops.

In assembling the reenforcement, one of the long spacing wires is applied to the long spiral A, the coils of the spiral being arranged within the open loops 4 so as to 30 locate the alined eyes 1 inside of the spiral. After this has been done, a long bar B is inserted through the alined eyes 1 to confine the coils in the U-shaped loops 4, the open sides of said loops being closed by the 35 bar B as shown in Fig. III. The bar B is then manipulated, as will be presently described, to prevent accidental displacement of the elements of the reenforcement.

Attention is now directed to Figs. I, IV 40 and V which show that the loops 1 are non-circular, and that the bars B are non-circular in cross section. Each eye 1 is yieldable and provided with a recess 5 in its inner face, said recess being formed by diverging 45 portions of the wire. Each bar B is provided with relatively sharp longitudinal edges adapted to enter the recesses 5 in the yielding eyes 1 (Fig. V) so as to secure the spacing device to the bar. The yielding 50 eyes 1 serve as detents which cooperate with the bars B to prevent displacement of the bars and spacing device. When a bar B is located as shown in Fig. IV, it will pass freely through the gripping eyes 1, and after 55 the bar has been properly located, it is turned to the position shown by Fig. V.

In Figs. I to V, the gripping eyes 1 are in the form of ovals, and the cross section of each bar B is in the form of an oval. 60 The major axis of the bar is longer than the minor axis of the oval formed by the inner faces of an eye 1, so when the bar B is turned to the position shown in Fig. V, the eye 1 will be distorted to firmly grip the 65 bar.

In Fig. VI, the bar B' is rectangular in cross-section and the gripping eye 1' is rectangular. When the bar B' occupies the position shown by dotted lines in Fig. VI it can be freely inserted into the eye 1', but when said bar B' is turned to the position shown by full lines, one of its sharp longitudinal edges will be forced into the recess 5', so as to secure the bar to the eye. 70

This invention is based upon new features 75 not disclosed in an application for patent filed by me on August 19, 1921 Serial No. 493,541 which contains claims broad enough to cover the spacing device herein described.

I claim:

1. In a reinforcing structure, a series of reinforcing elements, a bar crossing said reinforcing elements, said bar having a cross sectional shape of varying dimensions and a spacer comprising a row of yieldable eyes surrounding and adapted to interlock with said bar, spacing elements uniting said eyes, and a row of loops extending from said spacing elements and embracing said reinforcing elements, said bar being movable relative to said eyes and provided with means to interlock said eyes with said bar. 90

2. In a reinforcing structure, a series of reinforcing elements, a bar crossing said reinforcing elements, said bar having a cross sectional shape of varying dimensions and a spacer comprising a row of eyes surrounding said bar, spacing elements uniting said eyes, and a row of loops extending from said spacing elements and embracing said reinforcing elements, said eyes being yieldable to provide yielding detents adapted to interlock with said bar, and said bars being rotatable to cooperate with said detents. 95

3. In a reinforcing structure, a series of reinforcing elements, a bar crossing said reinforcing elements, said bar having a cross sectional shape of varying dimensions and a spacer comprising a row of eyes surrounding said bar, spacing elements uniting said eyes, and a row of loops extending from said spacing elements and embracing said reinforcing elements, said eyes being yieldable and provided with recesses, and said bar being movable in said eyes and provided with a longitudinal edge adapted to enter said recesses, so as to interlock said bar with said eyes. 110

4. In a metal reinforcement for concrete 120 columns, a reinforcing member in the form of a spiral, a bar arranged longitudinally of the spiral and engaged with the inner faces of the coils of the spiral, said bar having a cross sectional shape of varying dimensions, and a spacer for said coils, said spacer comprising a single piece of wire provided with a row of gripping eyes surrounding said bar, spacing elements uniting said eyes, and U-shaped loops extending 125 130

from said spacing elements and embracing the coils of said spiral, said loops and eyes being extended from opposite sides of said spacing elements, the U-shaped loops being closed by said bar, said eyes being yieldable and provided with recesses, and said bar being rotatable in said eyes and provided

with a longitudinal edge adapted to enter said recesses to interlock said bar with said eyes. 10

In testimony that I claim the foregoing I hereunto affix my signature.

JAMES C. SHEPHERD.
